UNITED STATES PATENT OFFICE.

JOHN F. GAIL, OF KENOSHA, WISCONSIN.

SATIN-FINISH MACHINE.

1,107,214.

Specification of Letters Patent. Patented Aug. 11, 1914.

Application filed May 2, 1913. Serial No. 765,069.

To all whom it may concern:

Be it known that I, JOHN F. GAIL, a citizen of the United States, residing at Kenosha, in the county of Kenosha and State of Wisconsin, have invented certain new and useful Improvements in Satin-Finish Machines, of which the following is a specification.

This invention relates to metal finishing machines, and particularly to such a machine adapted for imparting to brass what is known as the satin finish as distinguished from a smooth high polish.

The primary object of the invention is the provision of an automatically operating machine whereby objects of metal such as brass mounts for beds and the like may be given a uniform satin finish in a most economical and efficient manner. Requiring no manual attention other than the placing and removal of the work pieces, the product of the machine is rendered uniformly excellent and independent of the varying skill of different operatives, as distinguished from hand work, and the cost of production is also reduced to a minimum.

In order that the invention and the manner of its use may be the more readily understood by those skilled in the art, I have set forth in the accompanying drawings and in the following detailed description based thereon a preferred embodiment of the invention, it being understood that such drawings and description are to be taken as illustrative only and not in an unnecessarily limiting sense.

In these drawings, Figure 1 is a front elevation of a machine embodying the invention; Fig. 2 is an elevation showing the right hand end of the machine illustrated in Fig. 1; Fig. 3 is an elevation showing the left hand end of said machine; Fig. 4 is a detail sectional view through the work holder driving member; Fig. 5 is a fragmentary view of the abradant carrier; Fig. 6 is a vertical longitudinal section through the work holder; Fig. 7 is a vertical longitudinal section through the main driving mechanism of the machine; and Fig. 8 is a side elevation of the work holding chuck removed from its mounting.

In the embodiment of the invention shown and having particular reference to the drawings, the machine comprises the frame 11 to which are secured as a substantially in-

tegral part by means of the clamping members 12, the vertical guides 13, 13 and a transverse member 14 at the top of the machine. Upon the cross member 14 at the point of intersection between said member and the guides 13 are mounted peripherally grooved guide rollers 15, 15 and at an intermediate point upon the cross member 14 a pair of similar guide rollers 16, 16 is mounted, the last named rollers being journaled slightly out of vertical alignment as shown.

Upon the machine frame and between the guiding rollers, above described, are adapted to be mounted a plurality of machine units side by side. For the purposes of this description I have illustrated two units each a duplicate of the other and each comprising a reciprocating frame in the form of a yoke, the side members 17, 17 of which are rigidly connected below with the transverse I-beam 18, which beam is guided for vertical reciprocating movement by sleeves 19, 19 sliding upon the guides 13 while the upper portions of the side members 17 are guided between the rollers 15, 16. The yoke frame is counter balanced by means of counter weights 20, 20 attached to cords 21, 21 passing over sheaves 22, 22. Each of the yokes is provided in its lower portion with clips 23 and also above with similar clips 24, one set secured to each of the side members 17 by brackets 25, 25. To each of the clips are attached a plurality of strands 26 of wire or the like and to the other end of each of such strands is attached a light contractile spring 27, while connecting the opposed ends of adjacent springs of each set are bundles of fibers of cord or the like 28, 28. These bundles of cords are adapted to be heavily impregnated with an abradant material such as Tripoli composition, fine emery or other suitable material dependent upon the metal to be finished and the particular finish to be given. In Fig. 1 of the drawing I have indicated each of the bundles of fiber with a single line, although in practice each of said bundles is composed of a large number of fibers as indicated in detail in Fig. 5.

Each of the side members 17 of the yoke frames together with its bracket 25, clips 24 and abradant strands 26 is so mounted in the machine as to be readily removed and replaced. The lower end of each member is

confined laterally between side and rear stops 18^a while its brackets 25 has depending lips 25^a which overlie one end of a leaf spring 18^b secured in its medial portion on the beam 18. The tension of the spring 18^b presses the toe of the bracket 25 upward and holds the upper end of the member 17 yielding outward within the groove of the roller 15. When it is desired to remove one of the members 17 the upper end is pressed inward against the tension of the spring 18^b until it clears, the roller 15 is then swung around the roller upon its lower end as a fulcrum and its lower bracket lifted from the spring 18^b and free from the machine. A new member will be inserted by an obvious reversal of this operation.

In order to impart to the yoke frame a vertical reciprocating motion as stated, and to reverse such movement at the upper and lower limits of travel, I provide the following described mechanism: Upon the drive shaft 29 is fixed a drive pulley 30 and upon the two sides of the pulley 30 are loosely mounted drive pulleys 31, 32, adapted to be driven in opposite directions by usual belt connections. The shaft 29 suitably journaled in the machine frame carries upon its forward end a worm gear 33 by which is driven a counter shaft 34 likewise journaled in the machine frame and carrying at each end a pinion 35. Each of the pinions 35 is in mesh with one of a pair of racks 36 carried by the side members 17 of the reciprocating yoke whereby, as will be obvious, the yoke is moved in a vertical direction by the rotation of the pinions 35. In order to reverse the direction of movement of the drive shaft 29 and with it that of the yoke, I provide a belt shifting device in which a shifting bar 37 fitted with belt engaging arms 38, 38 is mounted for movement parallel to the shaft 29 to shift the belts upon the tight and loose drive pulleys. The shifting bar 37 carries a stud 39 which is engaged by the slotted arm 40 of an angle lever, the other end 41 of which has connected thereto a rod 42 provided at its free end with an adjustable stop such as the nuts 43. A projection 44 from the cross beam 18 of the yoke slidably engages the rod 42 playing thereon between the end of the arm and the stop 43. Carried by the shifting bar 37 is a friction catch 45 having inclined end faces as indicated at 46, 46, and intermediate side recesses 47, 47. A pair of arms 48, 48 are pivoted at one end to the machine frame and at the other end provided with rollers 49, 49 bearing upon the catch 45, the said arms being connected by a contractile spring 50. In Fig. 3, for example, the yoke is shown as nearing the limit of its downward movement at which time the projection 44 will engage the stop 43 and move the rod downwardly shifting the angle lever and there-

with the shifting bar 37 to the right, causing the rollers 49 to ride up on to the friction catch 45 and down upon the opposite side thereof shifting the driving belt from the fixed pulley 30 to the loose pulley 32 and at the same time shifting the belt from the loose pulley 31 to the fixed pulley 30 thereby reversing the direction of rotation of the shaft 29 and causing the rack 36 and with it the yoke to move in an upward direction. When the yoke reaches the upper limit of its path a stop 44 engages the arm 41 of the angle lever shifting the same in the opposite direction and with it moving the shifting bar 37 to the left thereby shifting the driving belt from the fixed pulley 30 to the loose pulley 31 and the belt from the loose pulley 32 on to the fixed pulley 30, thus again reversing the direction of rotation from the drive shaft 29 and causing a renewal of the downward movement of the yoke.

Each unit of the machine includes a work holding arm 51 pivoted at 52 and yieldingly drawn to the right by a suitably anchored spring 53; likewise pivoted at 52 is a second arm 54 extending at substantially right angles to the arm 51 and having a branch 55 projecting therefrom substantially parallel to the arm 51. The branch 55 has mounted therein a threaded adjusting screw 56 provided with a hand wheel 57 the end of the screw serving as an abutment for the arm 51 and regulating the angle between the work arm 51 and the second arm 54, the former being held against the screw by the tension of the spring 53.

Upon the upper end of the work holding arm 51 is mounted the work holder which will be described hereafter more in detail, the function of such holder being to support in operative relation to the fibers and abradant carriers 28, 28a a work piece, such for instance as a terminal cap or mount for brass beds. It is desired that during the movement of the yoke and with it the abradant carriers in one direction the work holder shall hold the mount in contact with one set of abradant carriers and during the reverse movement of the yoke shall swing such mount in the opposite direction into contact with the other set of abradant carriers and in order to accomplish this periodic swinging movement of the work holder arm 51 upon its pivot 52 and to provide at the same time for the rotation of the work holder and mount the following mechanism is employed: Upon the outer end of the arm 54 is mounted a roller 58 adapted to travel upon the edge of a cam 59 fixed upon the cam shaft 60. The contour of the cam is such that during one complete revolution of the same the arm 51 is first swung to one side to bring the work piece into contact with one set of abradant fibers and then to the other 136

side into contact with the other set of abradant fibers, and lastly to the intermediate inoperative position illustrated in Fig. 1.

The cam shaft 60 has mounted thereon a 5 drive pulley 61 loosely engaged by a slowly moving drive belt 62, the operative connection between the loose belt 62 and the drive pulley 61 is secured by means of a belt tightening device comprising a lever 63 carrying 10 an idler pulley 64 in the plane of the belt and adapted to be brought into engagement with the same, while the opposite end of the lever is connected by means of a rod 66 with a treadle lever 67 having a foot piece 68 projecting above the floor in a position convenient to the operator. It will be readily understood that if the foot piece 68 is depressed the idler pulley 64 will be brought into engagement with the belt 62 to tension the 15 same and thereby cause the driving of the pulley 61 during such time only as such engagement is maintained. In order to maintain the foot piece in depressed position I provide a trip rod 69 pivoted to the treadle 20 lever 67 and provided with a lug 70 having a beveled lower face and an abrupt upper face adapted to engage below another lug 71 upon the machine frame, the trip lever 69 being yieldingly drawn to the right by a 25 suitably anchored spring 69^a. In order to provide for the automatic stopping of the cam at the end of each complete revolution I mount upon the pulley 61 a stud 72, into the path of which projects the upper end of the 30 trip lever 69. The engagement of the stud with the trip lever 69 serves to move the same to the left, as shown in Fig. 2, releasing the engagement between the lugs 70 and 71 and permitting the idler pulley 64 to 35 drop out of engagement with the belt 62 whereby the cam 59 is brought to rest with the work holder occupying the inoperative position shown in Fig. 1.

The work holder includes a chuck having 40 a head 73 formed as a hollow casing within which reciprocates a wedge member 74, the inclined faces 75 of which engage with pawls 76 pivoted at 77 causing the same, as the wedge member is moved in one direction, 45 to project radially through slots 78 of the head 73 while permitting the said pawls 76 to drop within said head when the wedge member is moved in the opposite direction.

The head is of a shape adapted to fit within 50 the work piece which is here shown as a mount 79, the outer face of the pawl 76 engaging the inner walls of the mount and holding the same securely thereon. The wedge member 74 is carried by a rod 74^a 55 slidably mounted within a sleeve 81 and abutting against a rod 80 provided with a vertical slot 82 by means of which the rod 80 is permitted a limited movement upon each side of a pin 83 extending transversely 60 through the slot 82, the said pin 83 being

fixed in the hub 84 of a disk 85 forming one member of a friction clutch by means of which the drive pulley 86 is connected and disconnected from the work holding clutch. A spring 87 encircles the rod 74^a bearing at 70 one end upon the fixed member 88 and at the other end upon a shoulder 89 formed upon the rod 74^a whereby the rod is yieldingly pressed to the right as illustrated in Fig. 6. The rod 80 extends beyond its bearing in the 75 sleeve 81, the projecting end of the rod being in axial alignment with a shifting rod 90 slotted at 91 for movement upon a stud 92 and pivoted at 93 to a lever arm 94 which latter is pivoted at 95 to the machine frame 80 and has its free end connected at 96 with a suitably anchored spring 97 and also connected at 98 with a cord 99 passing over the sheave 100 and attached at 101 to a treadle lever 102 mounted beneath the machine and 85 provided with a foot piece 103.

It will be seen that if the operator presses upon the foot piece 103, the lever 94 will be swung to the left causing the shifting rod 90 to impinge against the end of the 90 rod 80 and thereby move the same to the left from the position shown in Fig. 6, compressing the spring 87 and permitting the pawls 76 to be retracted within the head by the action of the contractile springs 104 to 95 release the mount. Concurrently the engagement of the left hand wall of the slot 82 with the pin 83 due to the tension of the spring 87 is relieved and the engagement of the opposite wall of the slot 82 with said 100 pin causes the movement of the latter together with the disk 85 to the left against the tension of the spring 105 thereby releasing the engagement between the friction surface 106 of the disk 85 and the constantly driven pulley 86 whereby the rotation of the chuck ceases and the mount may be removed from the head 73 and another substituted. Thereupon when the operator having released the foot piece 103, the rods 110 74^a and 80 are again moved to the right securing the mount upon the head and also clutching the friction disk to the drive pulley whereby the rotation of the clutch again 115 ensues.

From the foregoing it will be readily understood that during one revolution of the slowly moving cam 59 the work piece will be swung by the work holder arm to one side into contact with the multiplicity of fibers 120 charged with an abrading material and held in such position that substantially one-half of the surface of the mount will be buried in such bundle of fibers. While so held the yoke upon which the abradant carrier fibers are strung will be vertically reciprocated so as to bring the different portions of the fibers successively into contact with the work piece, which will be rapidly rotating 125 with the head of the work holder. After 130

the cam has completed nearly one-half of its revolution the work holder will swing in the opposite direction to bring the work piece into the same relation to the other abradant carrier upon the same yoke and will there hold the rapidly rotating work piece half buried in the bundle of fibers on that side. At the completion of the second stage of the cam the work holder will be swung to the intermediate inoperative position illustrated in Fig. 1, and the work piece or mount thus brought out of contact with the reciprocating abradant carriers, whereupon the revolution of the cam 59 will cease by reason of the engagement of the stop 72 with the trip lever 69 and the rotation of the clutch and the release of the work piece will be effected by the operator stepping upon the foot piece 103. He will then remove the mount from the chuck and substitute another; immediately thereafter releasing the foot piece 103 and depressing the foot piece 68 in order to start the machine anew. The operator may then turn his attention to the next unit in the machine to remove the finished work piece from such unit and substitute another during the automatic imparting of a satin finish to the mount held in the first unit.

I claim:

30 1. In a machine of the character described, the combination of an abradant-carrier composed of a bundle of loosely associated contacting fibers, a work holder arranged to hold a work piece in contacting relation with the carrier, and means to produce relative contacting movement between the holder and carrier longitudinally of the fiber of the latter, substantially as described.

40 2. In a machine of the character described, the combination of an abradant-carrier composed of a bundle of loosely associated contacting fibers, a rotatable work holder arranged to hold a work piece in contacting relation with the carrier, and means to produce relative contacting movement between the holder and carrier longitudinally of the fiber of the latter, substantially as described.

50 3. In a machine of the character described, the combination of an abradant-carrier composed of a bundle of loosely associated contacting fibers, a rotatable work holder arranged to hold a work piece in contacting relation with the carrier, and means to reciprocate the carrier longitudinally in contact with the work piece, substantially as described.

60 4. In a machine of the character described, the combination of an abradant-carrier composed of a bundle of loosely associated contacting fibers charged with an abradant, a rotatable work holder arranged to hold a work piece substantially half buried in the bundle of fibers, and means to reciprocate the fibrous carrier longitudi-

nally in contact with the work piece, substantially as described.

5. In a machine of the character described, the combination of an abradant-carrier composed of a bundle of independent contacting fibers charged with an abradant and held under yielding tension, a rotatable work holder arranged to hold a work piece substantially half buried in the bundle of fibers, and means to impart a reciprocating relative movement to the holder and carrier longitudinally of the latter, substantially as described.

6. In a machine of the character described, the combination of a pair of fibrous abradant-carriers, a work holder mounted therebetween to swing the work piece into contacting relation with the carriers in alternation, and means to produce relative contacting movement between the holder and carriers longitudinally of the fiber of the latter, substantially as described.

7. In a machine of the character described, the combination of a pair of abradant-carriers, each composed of a bundle of fibers assembled in substantially parallel relation, a work holder mounted therebetween to swing the work piece into contacting relation with the carriers in alternation, and means to produce relative contacting movement between the holder and carriers longitudinally of the latter, substantially as described.

8. In a machine of the character described, the combination of a pair of abradant-carriers each composed of a bundle of contacting fibers charged with an abradant and under yielding tension, a work holder mounted therebetween to swing the work piece into contacting relation with the carriers in alternation, and means to produce relative contacting movement between the holder and carriers longitudinally of the latter, substantially as described.

9. In a machine of the character described, the combination of a pair of fibrous abradant-carriers, a rotatable work holder mounted therebetween to swing the work piece into contacting relation with the carriers in alternation, and means to produce relative contacting movement between the holder and carriers longitudinally of the fiber of the latter, substantially as described.

10. In a machine of the character described, the combination of a pair of abradant-carriers, each composed of a bundle of fibers assembled in substantially parallel relation, a rotatable work holder mounted therebetween to swing the work piece into contacting relation with the carriers in alternation, and means to produce relative contacting movement between the holder and carriers longitudinally of the latter, substantially as described.

11. In a machine of the character de-

- scribed, the combination of a pair of abradant-carriers, each composed of a bundle of fibers charged with an abradant and under yielding tension, a rotatable work holder 5 mounted therebetween to swing the work piece into contacting relation with the carriers in alternation, and means to produce relative contacting movement between the holder and carriers longitudinally of 10 the latter, substantially as described.
12. In a machine of the character described, the combination of a pair of fibrous abradant-carriers mounted to reciprocate, and a work holder mounted therebetween to 15 swing the work piece into contacting relation with the carriers in alternation, substantially as described.
13. In a machine of the character described, the combination of a pair of fibrous 20 abradant-carriers mounted to reciprocate, and a rotatable work holder mounted therebetween to swing the work piece into contacting relation with the carriers in alternation, substantially as described.
14. In a machine of the character described, the combination of a pair of abradant-carriers mounted to reciprocate, each 25 comprising a bundle of fibers charged with abradant and arranged in substantially parallel relation under yielding tension, a work 30 holder mounted therebetween to swing the work piece into contacting relation with the carriers in alternation and to hold the same substantially half buried within the 35 bundle of fibers, substantially as described.
15. In a machine of the character described, the combination of a pair of abradant-carriers mounted to reciprocate, each 40 comprising a bundle of fibers charged with abradant and arranged in substantially parallel relation under yielding tension, a rotatable work holder mounted therebetween to swing the work piece into contacting relation with the carriers in alternation and 45 to hold the same substantially half buried within the bundle of fibers, substantially as described.
16. In a machine of the character described, the combination of a movable frame, 50 an abradant-carrier composed of a bundle of fibers charged with abradant and stretched within the frame, a rotatable work holder mounted to hold the work piece half buried within the bundle of fibers, and 55 means to reverse the movement of the frame and carriers, substantially as described.
17. In a machine of the character described, the combination of a reciprocating frame, a pair of fibrous abradant-carriers 60 strung therein, a rotatable work holder mounted between the carriers to swing the work piece into contact with the carriers in alternation, and means to automatically reverse the direction of movement of the 65 frame, substantially as described.
18. In a machine of the character described, the combination of a reciprocating frame, a pair of fibrous abradant-carriers strung therein, a rotatable work holder mounted between the carriers to swing the 70 work piece into contact with the carriers in alternation, means to automatically reverse the direction of movement of the frame, and means to automatically intermit the action of the machine at predetermined intervals, substantially as described. 75
19. In a machine of the character described, the combination of a pair of fibrous abradant carriers mounted to reciprocate, a rotatable work holder mounted therebetween 80 to swing the work piece into contacting relation with the carriers in alternation, means to automatically reverse the direction of movement of the carriers comprising a belt shifting device, and a lever having one 85 arm connected to the belt shifting device and the other arranged to be actuated at the limits of travel of the carriers, substantially as described.
20. In a machine of the character described, the combination of a reciprocating frame, a pair of fibrous abradant-carriers yieldingly strung therein, a rotatable work holder mounted between the carriers to swing a work piece into contact with the 90 carriers in alternation, means to reciprocate the frame, means to automatically reverse the direction of movement of the frame comprising a belt shifting device, and a lever having one arm connected to the belt 95 shifting device and the other arranged to be actuated by the reciprocating frame at the two limits of its movement, substantially as described. 100
21. In a machine of the character described, the combination of a reciprocating frame, a pair of fibrous abradant-carriers yieldingly strung therein, a rotatable work holder mounted between the carriers to swing a work piece into contact with the 105 carriers in alternation, means to reciprocate the frame, means to automatically reverse the direction of movement of the frame comprising a belt shifting device, and a lever having one arm connected to the belt 110 shifting device and the other provided with an extension having thereon a stop, the frame provided with a projection operating between the stop and end of the lever to actuate the latter at the two limits of the 115 path of movement of the frame, substantially as described.
22. In a machine of the character described, the combination of a reciprocating frame, a pair of fibrous abradant-carriers 120 strung therein, a rotatable work holder mounted between the carriers to swing a work piece into contact with the carriers in alternation, means to reciprocate the frame, and means to automatically re- 125 130

verse the direction of movement of the frame comprising a pair of reversely driven loose pulleys, an intermediate tight pulley, a pair of reversely moving belts mounted on the 5 loose pulleys, a belt shifter engaging the two belts, an angle lever engaging the shifter with one arm and having its other arm provided with an extension having a terminal stop, a part of the frame playing 10 between the second arm of the lever and the stop to actuate the lever at the extremes of movement of the frame, substantially as described.

23. In a machine of the character described, the combination of a reciprocating frame, a pair of fibrous abradant-carriers yieldingly stretched within the frame, a rotatable work holder mounted between the carriers to swing a work piece into contact 20 with the carriers in alternation, and means to automatically intermit the action of the machine at predetermined intervals comprising a pivoted arm carrying the work holder, a cam acting on the arm to oscillate the 25 same, a pulley carried by the cam shaft, a driven belt loosely engaging the pulley, a belt tightening device, means to retain the 30 tightener in action, and automatically operating means to throw the tightener out of action at stated intervals, substantially as described.

24. In a machine of the character described, the combination of a reciprocating frame, a pair of fibrous abradant-carriers 35 yieldingly stretched within the frame, a rotatable work holder mounted between the carriers to swing a work piece into contact with the carriers in alternation, and means to automatically intermit the action of the 40 machine at predetermined intervals comprising a pivoted arm carrying the work holder, a cam acting on the arm to oscillate the same, a pulley carried by the cam shaft, a driven belt loosely engaging the pulley, a 45 belt tightening device, means to retain the tightener in action, and automatically operating means to throw the tightener out of action at stated intervals comprising a stud carried by the cam, and a trip device mounted 50 in the path of the stud, substantially as described.

25. In a machine of the character described, the combination of a reciprocating frame, a pair of fibrous abradant-carriers 55 yieldingly stretched within the frame, a rotatable work holder mounted between the carriers to swing a work piece into contact with the carriers in alternation, means to automatically intermit the action of the machine at predetermined intervals comprising a pivoted arm carrying the work holder, a second arm pivoted concentrically therewith, a cam acting on the second arm to oscillate the same and with it the work holder arm, 60 a pulley carried by the cam shaft, a driven 65

belt loosely engaging the pulley, a belt tightener device, means to retain the tightener in action, and means to throw the tightener out of action at the termination of each revolution of the cam, substantially 70 as described.

26. In a machine of the character described, the combination of a reciprocating frame, a pair of fibrous abradant-carriers yieldingly stretched within the frame, a 75 rotatable work holder mounted between the carriers to swing a work piece into contact with the carriers in alternation, means to automatically intermit the action of the machine at predetermined intervals comprising a pivoted arm carrying the work holder, a second arm pivoted concentrically therewith, a cam acting on the second arm to oscillate the same and with it the work holder arm, a pulley carried by the cam shaft, a 80 driven belt loosely engaging the pulley, a belt tightener device, means to retain the tightener in action, means to throw the tightener out of action at the termination of each revolution of the cam comprising a 85 stud carried by a cam, and a trip device mounted in the path of the stud, substantially as described.

27. In a machine of the character described, the combination of a reciprocating frame, a pair of fibrous abradant-carriers yieldingly stretched within the frame, a rotatable work holder mounted between the carriers to swing a work piece into contact with the carriers in alternation, means to 90 automatically intermit the action of the machine at predetermined intervals comprising a pivoted arm carrying the work holder, a second arm pivoted concentrically therewith, means to adjust the angular relation of the 95 two arms, a cam acting on the second arm to oscillate the same and with it the work holder arm, a pulley carried by the cam shaft, a driven belt loosely engaging the pulley, a belt tightener device, means to retain the 100 tightener in action, means to throw the tightener out of action at the termination of each revolution of the cam comprising a stud carried by a cam, and a trip device mounted in the path of the stud, substantially 105 as described.

28. In a machine of the character described, the combination of a reciprocating frame, a pair of fibrous abradant-carriers yieldingly stretched therein, and a rotatable 110 work holder mounted between the carriers to swing the work piece in contact with the carriers in alternation, said work holder comprising a rotary sleeve, a friction disk mounted thereon to rotate therewith, a drive 115 pulley mounted in operative relation to the friction disk, a chuck carried by the sleeve, rotary acting work engaging members within the chuck, a wedge member arranged to act upon the retaining members and 120

slidable within the sleeve, a shifting rod |
slidable within the sleeve and having a |
slide and pin connection with the friction |
disk and also connected to the wedge mem- |
ber, and means to actuate the shifting rod |
to simultaneously retract the work retaining |
members and disengage the friction disk |

from the drive pulley, substantially as de- |
scribed.
